UNITED STATES PATENT OFFICE.

THOMAS E. GRIFFITH AND LEE L. DODDS, OF CLEVELAND, OHIO, ASSIGNEES TO THE
W. S. TYLER COMPANY, OF CLEVELAND, OHIO, A CORPORATION OF OHIO.

SWITCH MECHANISM.

Application filed March 5, 1923. Serial No. 623,058.

The present invention, relating, as indicated, to switch mechanism, is more particularly directed to an improved type of quick-opening switch for use in connection with elevator doors. It is desirable to provide means in connection with elevator enclosure doors for breaking the operating circuit for the car as soon as the doors of the enclosure are open and for maintaining the circuit open as long as the doors are open. The present invention is directed to an improved type of switch for this purpose. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a front elevation of an enclosure and door therefor, together with our improved switch mechanism; Fig. 2 is a longitudinal central section through the switch mechanism; Fig. 3 is a section on the line 3—3, Fig. 2; Fig. 4 is a section on the line 4—4, Fig. 2; Fig. 5 is an end elevation of the switch mechanism; and Fig. 6 is a side elevation of the actuating means for the switch.

In Fig. 1 there is shown an elevator enclosure, provided with a door 2, locking member 3 and latch 4 therefor, and carriage 5, which slidably supports the door. Mounted above the door on the enclosure 1 is a switch mechanism enclosed in a casing 6.

The switch mechanism consists of contact elements 7 and 8, to which are respectively connected wires 9 and 10 which enter the interior of the casing 7 through openings 11 and 12 therein. These contact members 7 and 8 are adapted to be bridged and thus placed in electrical connection to close the operating circuit for the elevator car by means of a switch member 15 provided with a head portion 16 of sufficient breadth to engage both of the elements 7 and 8 when the switch member is in the position shown in Fig. 2. The switch member 15 is of resilient metal and is secured to the bar 17 of fiber or other insulating material which is secured to a shaft 18. The bar 17 extends

on the other side of the shaft 18, and this end 18 of the bar is weighted sufficiently to normally raise the switch member into the position shown in dotted lines in Fig. 2. A buffer 20, of some soft yielding material, is mounted in the base of the casing 7 for cushioning the impact of the end 19 of the switch member when the latter is opened.

The shaft 18 extends through the side of the casing 6 where it carries a link 25 provided with a roller 26 on its lower end, this link being fixed to the shaft, and turning with the shaft.

Mounted on the top of the carriage 5 are two trackways, one of the trackways 30 being inclined slightly to the horizontal during the greater part of its length, and having a terminal portion 31 which is horizontal. The second trackway 32 is pivotally connected to the first about a pin 33 as an axis, and in its normal position, which is shown in dotted lines in Fig. 6, is also horizontal.

The operation of the switch mechanism is as follows: The roller 26 normally rests upon the flat horizontal end 31 of the inclined trackway when the door is in the closed position shown in Fig. 1. As this door is moved to the left the carriage and trackway are similarly moved and the roller drops off from the end of the pivoted trackway 32, thus permitting the counterweighted end of the member 17 to swing said member in a clockwise direction, lifting the switch element 16 out of contact with the two switch terminals 7 and 8, and in this way breaking the circuit for the car. Upon the return of the door to its closed position the roller 26 engages against the lower end of the inclined track 30 (see Fig. 5), and is carried up on the inclined trackway to the upper flat portion 31. When the roller reaches this portion the shaft 18 has been rotated sufficiently to return the switch element 16 into contact with the members 7 and 8, closing the circuit. During the movement of the roller up the inclined surface 30, it engages beneath the upper trackway 32 and lifts this sufficiently to permit the roller 26 to continue up the inclined trackway, as shown in Fig. 6, until it reaches the flat portion which is beyond the end of the pivoted trackway so that the latter then drops back to its normal horizontal position.

The present switch mechanism gives an

extremely quick switch opening and is simple in construction. Our novel device also provides a safety mechanism for elevators because electrical connection is not effected until the car door 2 is completely closed, at which time the roller 26 is held in the portion 31 and connection is made by the switch mechanism between the contact members 7 and 8.

10 We therefore particularly point out and distinctly claim as our invention:

1. The combination of a pivotally mounted switch member; contact members cooperating therewith; an operating link connected to said switch member; a horizontally sliding member consisting of an inclined plate adapted to engage the end of said link to rock said switch member about its pivot when said member is moved in one direction; and a pivoted trackway cooperating with said inclined trackway to hold said link and switch member in contacting relation during a part of the travel of said member in the opposite direction.

25 2. A switch mechanism comprising an enclosed casing, contact members carried therein, a horizontal shaft journaled in said casing, a switch member mounted on said shaft, a metallic head on one end of said switch

member adapted to engage said contact members, a counterweight on the other end thereof, an operating link mounted on said shaft outside the casing, a roller on the end of said link and horizontal sliding means adapted to engage said link to rock said shaft in one direction.

3. A switch mechanism comprising a casing, contact members carried therein, a horizontal shaft journaled in said casing, a switch member mounted on said shaft, a metallic head on one end of said member, a counterweight on the other end thereof, an operating link mounted on said shaft outside the casing, a horizontally sliding member consisting of an inclined plate adapted to engage the end of said link to rock said switch member about its pivot when said member is moved in one direction, and of a pivoted trackway co-operating with said inclined trackway to hold said link and switch member in contacting relation during a part of the travel of said member in the opposite direction.

Signed by us, this 20th day of February, 1923.

THOMAS E. GRIFFITH.
LEE L. DODDS.
